ADJUSTABLE GAS CONTROL VALVE

Timothy J. Sullivan, Butte, Mont., assignor to Sullivan Valve and Engineering Company, Butte, Mont., a corporation of Montana

Application May 8, 1956, Serial No. 583,893

2 Claims. (Cl. 236—80)

This invention pertains generally to gas control valves, and more particularly to means for adjustably setting the open positions of pressure-motor controlled full-flow supply valves. This application is a continuation-in-part of my earlier application Serial No. 570,894, filed March 12, 1956, now abandoned.

An object of my invention is to provide adjustable stop means limiting the open positions of a single-stage full-flow valve controlling the flow of a gaseous medium from a source to a demand.

Another object of my invention is to provide adjustable stop means on a two-stage pressure-motor valve in the supply main of a burner of a gas-fired boiler so that the low-fire and high-fire valve positions may be adjustably set as desired.

A further object of my invention is to provide pressure-motor controlled full-flow valves which will automatically close upon failure of the electrical power supply. My invention also includes the provision of solenoid holding means for manually holding the gas supply valve in the open position as desired.

Still another object of my invention is to provide two-stage control means effective to supply gas to the burner of a boiler or the like so as to operate the burner on low-fire when initially starting up until the stack is heated and when there is less demand upon the system, and on high-fire after the system is heated up to take the peak demand and when there is a high demand upon the same, and including means for adjustably setting the low-fire and high-fire valve positions.

A further object of my invention is to relate the adjustable operation of a pressure-motor controlled gas supply valve with a secondary air supply damper so as to insure adequate air supply at all times.

Other objects and advantages of my invention will become more apparent from a study of the following specification when considered in conjunction with the accompanying drawings, in which:

Fig. 1 is a semi-schematic view of a two-stage valve system embodying the invention;

Fig. 2 is an axial sectional elevation of the two-stage control valve and operating means therefor;

Fig. 3 is a side elevation of the two-stage control valve showing the connections of the solenoids; and

Fig. 4 is an axial sectional elevation of the invention as applied to a single-stage full-flow valve.

Referring more particularly to the drawings, the invention is shown in Figs. 1-3 as applied to a steam boiler 1 equipped with a gas burner 2 fed with gas through a supply main 3 and equipped with a secondary air door 4 for controlling the admission of air thereto. The secondary air door 4 is adjusted by a chain 5 and lever 6 in accordance with the setting of the main gas supply valve 7, hereafter described in detail. Gas is supplied to the valve 7 through pipe 8 and the regulated flow from the valve 7 flows to the burner 2 through pipe 3. The arrangement

2

is similar to that disclosed in my prior Patent No. 2,333,212, titled "Control for Fuel Burners."

The flow of fuel through the valve 7 is controlled by pressure motors 9 and 10. The operation of the low-fire pressure motor 9 is under control of a solenoid operated three-way pilot valve 11 and the operation of the high-fire pressure motor 10 is under control of a solenoid operated three-way pilot valve 12.

The solenoid operator of pilot valve 12 is controlled by high-fire switch 13 responsive to steam pressure in the boiler pipe 14. The control switch 13 is connected to the solenoid pilot valve 12 by wires 15 and 16 and is connected in series with stack thermostat 17 which maintains the circuit to solenoid 12 open until the stack is heated to a desired temperature with the burner operating on low-fire regardless of the demand on the system.

The solenoid operator of pilot valve 11 is controlled by a low-fire switch 18 also responsive to the steam pressure in boiler pipe 14 and connected to the solenoid by wires 19 and 20. Power is supplied to the solenoid control circuits from power source 21 through step-down transformers 22 and 23.

Referring more particularly to Figs. 2 and 3, gas supply pressure from the valve 7 is admitted to the lower chambers 24 and 25 of pressure motors 9 and 10 respectively through tubes 26a and 26b. At four-way fitting 27 gas of the same supply pressure is admitted to the inlets 28a, 28b of the three-way solenoid valves 12 and 11 through tubes 29a and 29b. From outlets 30a and 30b of solenoid valves 12 and 11 gas may be admitted to the upper chambers 31 and 32 of fluid pressure motors 10 and 9 through tubes 33a and 33b. The solenoid valves 12 and 11 are also provided with vent outlets 34a and 34b and with vertically movable solenoid plungers 35a and 35b. If for example, solenoid 12 were energized, the plunger 35a would be drawn upwardly, closing opening 36a. The pressure in upper chamber 31 of valve 10 would then be opened to atmospheric pressure through tube 33a and vent 34a. Upon de-energization of solenoid 12, plunger 35a would drop, allowing connection between inlet 28a and outlet 30a through opening 36a. Upper chamber 31 is then connected to lower chamber 25 through tubes 33a, 29a and 26a and the pressures in both chambers will therefore be equal. Solenoid valve 11 provides similar operation between the upper and lower chambers 32, 24 of pressure motor 9.

Valve 7 is of the large-capacity full-flow valve type and has a valve member 37 adapted to cooperate with an annular seat 38 on a transverse wall 39 and is pivotally secured within the valve casing on pivot 40. Pivotally secured to valve member 37 at pivot 41 is connecting link 42 connected to vertically slideable lower stem 43. Lower stem 43 passes through diaphragm 44 which separates upper chamber 31 from lower chamber 25 and through pressure plates 45 and 46 clamped thereon and is fixed to the diaphragm and pressure plates by lock units 47 and 48 so that movement of the diaphragm 44 will be imparted to the stem 43, the connecting link 42 and the valve member 37 carried thereby.

Lower stem 43 is slidably guided within the upper portion of the casing 49 and is sealed therein by O-ring 50. As seen in Fig. 2, lower stem 43 extends through diaphragm 51, which separates upper and lower chambers 32 and 24, and through pressure plates 52 and 53 clamped thereon. Lower stem 43 is arranged to cooperate with the lower extremity of upper stem 54 which is pivotally secured at 55 to the lever 6. Lever 6 is pivoted about fixed pivot 55a and is connected at its extremity 55b through the chain 5 to the secondary air door 4, as shown in Fig. 1.

Rigidly secured to the diaphragm 51 and pressure

plates 52, 53 by locking members 54 and 55 is hollow shaft 56 which is slidably movable within sleeve 57. The O-ring 58 seals the shaft 56 within sleeve 57. Sleeve 57 is rigidly secured in an opening 59a in the upper portion 59 of the casing of low-fire pressure motor 9. The low-fire adjustable-setting member 60 is adjustably secured within the upper portion of sleeve 57 by screw-thread connections and carries on its outer surface a lock nut 61 for locking the position of adjustable-setting member 60.

Threadedly secured within the low-fire adjustable setting member 60 is the high-fire adjustable setting member 62 carrying a lock nut 63 for locking its position.

At the upper extremity of the stem 43 is a flanged extension 64. The aperture 56a in the lower surface of hollow shaft 56 allows passage therethrough so that the under surface of flanged extension 64 may contact and be carried by the upper surface of locking member 55. Upper stem 54 similarly has a flanged extension 65, the upper surface of which is arranged to contact the lowermost surface 66 of the high-fire adjustable setting member 62 and thus limit the upward travel of upper stems 54. The upward extent of travel of hollow shaft 56 within sleeve 57 is limited by the lowermost surface 67 of the low-fire adjustable setting member 60.

In operation the valve, when shipped from the factory to be put on the line, is in a closed position as shown in Fig. 2. The gas enters the valve chamber through pipe 8, fills the lower chamber 25, and passes through tubes 26a, 29a and 33a to the upper chamber 31 of pressure motor 10 so that equal gas pressure is on both sides of the diaphragm 44. Similarly the gas passes through tubes 26a, 26b, 29b, and 33b to admit gas to chambers 24 and 32 of pressure motor 9 to apply equal gas pressure on both sides of the diaphragm 51. The valve 37 is thus maintained in the closed position by the gas on top of the diaphragms, under the diaphragms, and against the valve 37.

When the low-fire solenoid valve 11 is actuated, its solenoid plunger, not shown, will be drawn upwardly by electromagnetic action, closing the connection between tubes 29b and 33b, and reducing the pressure of upper chamber 32 of the low-fire pressure motor 9 by venting tube 33b to the atmosphere. Since the pressure in lower chamber 24 is greater than the pressure in upper chamber 32, diaphragm 51 will move upwardly, carrying the hollow shaft 56 therewith. The upward movement of travel of shaft 56 will be limited by the position of the low-fire adjustable setting member 60. As hollow shaft 56 moves upwardly, the upper surface of member 55 contacts flange 64 of stem 43 and carries stem 43 upwardly. Diaphragm 44 and connecting link 42 are carried upwardly, and valve 37 is pivoted about pivot 49 to its low-fire open position.

For the high-fire open position of valve 37 the solenoid valve 12 is energized, pulling the plunger upwardly to close the opening 36a. Upper chamber 31 is vented to the atmosphere through tube 33a, opening 68a, and vent 34a. Since the pressure in lower chamber 25 is thus greater than upper chamber 31, diaphragm 44 moves further upwardly. As stem 43 carried by diaphragm 44 moves upwardly, its upper surface 68 contacts the lowermost surface of upper stem 54 and forces stem 54 upwardly until the extension 65 contacts the lowermost surface 66 of the high-fire adjustable setting member 62. Valve 37 will be further pivotally opened to the high-fire open position. Thus it may be seen that the amount of gas flow desired for either high-fire or low-fire operation may be readily set by adjusting the positions of the low-fire adjustable setting member 60 and the high-fire adjustable setting member 62. This type of integral valve adjustment may be set and locked into position with the lock nuts 61, 63, which adjustment is not effected during system shut down. The advantages of this integral unit are obvious over the control valves

of the prior art which utilize auxiliary firing valves and generally require a complete new test and setting when the operation of the system is temporarily discontinued.

Upon electric power failure, the solenoid plungers of solenoid valves 11 and 12 drop. Lines 29b, 33b and 29a, 33a are connected, the pressures in the upper and lower chambers 32, 24, 31 and 25 become equal, and valve 37 drops to its closed position, discontinuing the admission of gas to the gas burner.

When electrical power is first applied to the system and valve 7 is fully closed, the pressure responsive switches 13 and 18 will be closed due to the lack of boiler pressure. However, because stack switch 17 is open, solenoid 12 will not be energized. Solenoid 11 will be actuated to place valve 37 in its low-fire open position. As soon as the stack heats up sufficiently on low-fire to close the stack switch 17, the circuit to the high-fire solenoid 12 will be completed, causing valve 37 to assume its high-fire open position and admit full flow of gas to the burner.

As seen from Fig. 2, the three-way solenoid valves are provided with a mechanical holding arrangement whereby in the event of power failure, the solenoid plungers may be maintained in their up positions to vent the upper chambers and maintain the valve 37 in either of the open positions. If, for example, solenoid plunger 35a of solenoid 12 were in the lower position, cap 69a might be removed, exposing the rod 70a slidably mounted within member 71a in the valve wall. Spring 72a biases rod 70 to the right as shown in Fig. 2. Rod 70a has an extension 73a with an inclined surface adapted to cooperate with the under surface 74a of the plunger 35a. Thus upon manual movement of the rod 70a to the left against the spring bias, plunger 35a is moved upwardly due to the cooperation between the inclined surface of extension 73a and the under surface 74a of the solenoid plunger. The extension 73a has a catch 75a which engages under surface 74a, holding the rod in engagement with the plunger upon release of the manual insertion pressure. Tube 33a would be connected with vent 34a, diaphragm 44 would be in its upper position, and the valve 37 would be in the high-fire open position. Upon reapplication of electrical power to the solenoid valve 12, the plunger 35a is drawn upwardly slightly disengaging the catch 75a from plunger surface 74a, allowing the spring 72a to automatically return the rod 70a to its normal position.

Referring now to Fig. 4, a single stage valve is disclosed having diaphragm 76 with valve stem 77 secured therethrough by means of the lock nuts 78 and the pressure plates 79. Connecting link 80 secured to the lower extremity of valve stem 77 is secured to valve member 81 so that when diaphragm 76 is in its lower position as shown in Fig. 4, valve member 81 is in its closed position, and when diaphragm 76 is in its upper position the valve member 81 is in its open position.

Secured to the upper portion of the pressure motor casing 82 is a sleeve 83 having a threaded interior bore. Threadably movable within the sleeve 83 is adjustable setting member 84. Setting member 84 has a hollow bore therethrough to permit vertical sliding movement of valve stem 77 therein. O-ring 85a in the sleeve 83 serves to seal the valve stem 77 and to prevent evacuation of the pressure motor. The valve stem 77 is provided with an extension 85 adapted to cooperate with the under surface 86 of adjustable setting member 84. Thus it may be seen from Fig. 4 that by vertically adjusting setting member 84 within sleeve 83 the extent of upward travel of stem 77 may be limited, and consequently the extent of opening of valve member 81 is likewise limited. Secured to the upper extremity of valve stem 77 is lever arm 77a pivoted about pivot point 77b and provides control means to the secondary air door 4 of Fig. 1 by means of the chain 5.

The operation of the pressure motor is controlled

by solenoid valve 87 having a line 88 connected to the upper pressure motor chamber 89 and a line 90 connected to the lower pressure motor chamber 91. Energization of the solenoid valve will cause line 88 to be connected to vent line 92 with the result that the pressure in lower chamber 91 is greater than the pressure in upper chamber 89. Diaphragm 76 then moves upwardly until extension 85 contacts lower surface 86 of adjustable setting member 84. Valve member 81 is thus moved to its open position.

Failure of electrical power supplied to solenoid valve 87 will result in the connection of lines 88 and 90 to equalize the pressures in upper chamber 89 and lower chamber 91 and to allow diaphragm 76 to drop and valve member 81 to close. The solenoid valve 87 is provided with the solenoid holding means 88 described above.

Thus it is apparent that my invention provides adjustable stop means for controlling the open positions of a pressure-motor controlled full-flow valve, and that my invention is equally applicable for single or plural stage units.

While in accordance with the provisions of the statutes I have illustrated and described the best form of embodiment of my invention known to me, it will be apparent to those skilled in the art that changes may be made in the form of the apparatus described without departing from the spirit of my invention as set forth in the appended claims.

I claim:

1. Control means for regulating the supply of gas in a supply main to a gas-fired vessel comprising a valve in said supply main having a valve casing divided into an inlet chamber and an outlet chamber by a partition provided with a valve seat and having a valve member in said inlet chamber cooperating with said valve seat, a high-fire pressure motor having a casing with a movable diaphragm therein, means connecting said movable high-fire diaphragm to said valve member comprising a connecting link connected at one end to said diaphragm and at the other end to said valve member whereby said high-fire diaphragm is operable by gas pressure to move said valve member to a fully open high-fire position, a low-fire pressure motor having a casing with a movable diaphragm therein, means connecting said movable low-fire diaphragm to said valve member whereby said low-

fire diaphragm is operable by gas pressure to move said valve member to a partially-open low-fire position, said low-fire diaphragm connecting means comprising a sleeve extending through and secured to the casing of said low-fire pressure motor, a hollow shaft secured to said low-fire diaphragm and slidably arranged within said sleeve, a lower stem secured to said high-fire diaphragm and slidably extending through said pressure motor casings and said low-fire diaphragm and terminating within said hollow shaft, said lower stem having a flanged extension at its upper extremity within said hollow shaft whereby it may be carried upwardly by upward movement of said low-fire diaphragm and thereby position said valve member in its low-fire position by means of said connecting link means for adjustably limiting the opening of said valve member in said low-fire and high-fire positions, and means for independently controlling the operation of said low-fire pressure motor to partially open said valve in response to a low demand for heat and to effect operation of said high-fire pressure motor to fully open said valve in response to high demand for heat.

2. Control means as defined in claim 1, wherein said adjustable limiting means comprise an upper stem slidably extending through said sleeve in said low-fire motor casing and terminating within said hollow shaft, said upper and lower stems being arranged in abutting cooperation, a flanged extension on said upper stem intermediate its ends within said sleeve, a low-fire setting member adjustably secured within said sleeve for adjustably limiting the upward extent of travel of said hollow shaft within said sleeve, and a high-fire setting member adjustably secured within said low-fire setting member cooperating with said flanged extension on said upper stem to adjustably limit the upward extent of travel of said upper stem within said sleeve, whereby the low-fire and high-fire open positions of said valve member may be adjustably determined as desired.
